UNITED STATES PATENT OFFICE.

EUGENE SIXTEN SANDBERG, OF ALLENTOWN, PENNSYLVANIA.

VIBRATORY DISTRIBUTOR OF ELECTRIC CURRENT.

Original application filed May 23, 1924, Serial No. 715,264. Revised and this application filed April 20, 1925. Serial No. 24,563.

This invention relates to a vibratory distributor of electric current, which is adapted to be operated in synchronism with another vibratory element by means of a periodically pulsating current. More specifically, it relates to a device adapted to be employed in an electrical communication system for distributing the components of a complex signalling current in a main line in proper sequence to respective branch lines leading therefrom, which device operates in synchronism with a similar distributor or mate at the other end of the main line. This apparatus is employed in my improved telegraph system, disclosed in Patent No. 1,565,507 granted Dec. 15, 1925, and of which the present application is a division.

One of the objects of the present invention is to provide a distributor of the kind described having a vibrator which can be tuned to the frequency of the operating pulsating current, and whose oscillations may be sustained by the application of an exceedingly small amount of electrical energy.

Another object is to provide means for regulating the amplitude of vibration of the vibrator independently of the operating pulsating current.

Other objects and advantages will appear in the course of the following description.

In the accompanying drawings forming part of this specification, in which like numbers of reference denote like parts wherever they occur,

Figure 1 is a plan view of an apparatus which includes a main distributing vibrator and two auxiliary vibrators made in accordance with this invention;

Figure 2 is an elevation of the same;

Figure 3 is a sectional view on the irregular line 3—3 of Figure 2;

Figure 4 is a fragmentary elevational view of one of the details of the instruments; and

Figure 5 is a sectional view on the line 5—5 of Figure 1.

The distributing vibrator 1 and two auxiliary vibrators 2 needed at each end of the main line, in the particular system disclosed in said prior application, are preferably mounted on a common insulating base or block 3, preferably slate, as shown in Figures 1, 2, 3, and 5. The armatures 4 of the vibrators are constructed of long rods of

spring steel, supported at their rear ends in posts 5, secured to the base 3 by bolts 6. The posts 5 are split at their upper ends to form jaws 7 for clamping the armatures 4, the said jaws being drawn together by screws 8.

The free end of each of the armatures 4 extends between the poles 9 of a pair of electromagnets 10. The poles 9 are preferably bored to fit the cylindrical cores 11 of the electromagnets 10, and are split as at 12 so that they may be tightly secured to the projecting ends of the cores 11 by means of the clamping screws 13. The other ends of the cores 11 project into the yoke 14, which yokes are bored to fit the cores 11 and split as at 15 to permit of clamping around the cores 11 by means of the screws 16. The yoke 14 is secured to the base 3 by screws 17.

The ends of the electromagnets 10 adjacent the pole pieces 9 are held within a rectangular frame comprising side members or posts 18, lower or base member 19, and upper member 20, the said members being fastened together in any suitable manner, and the lower member 19 being secured to the base 3 preferably by screws 21.

Cores 11, pole pieces 9, and yoke 14 are fabricated of soft iron, and magnetism is induced therein by a permanent magnet 22, of substantially L-shape comprising a major arm 23 extending across the top of the pair of electromagnets 10 from the yoke end of the pole end, and a minor arm 24, depending from the arm 23 at the yoke end. Pinnacles 25, preferably formed integral with arm 23, project laterally therefrom toward the posts 18, and are pivoted in bearings 26 formed in the ends of screws 27 threading in tapped holes 28 formed in the posts 18. Arm 24 normally tends to gravitate towards yoke 14, but its proximity to the yoke is limited by adjusting screw 29, borne by the projection 30 of brace 20, and impinging against the top of the projection 31 of the free end of the major arm 23.

Contact posts 32 are juxtaposed to the free ends of the armatures 4, being secured to the base 3 by bolts 33. The middle vibrator is the distributor, and it is to be noted that there are two contact posts associated therewith, one on each side of its armature; while the outside vibrators are the auxiliaries and are each provided with but a sin-

gle contact post. The contact posts are provided with contact screws 34, provided with the usual contact points 35 of platinum-iridium or other suitable contact material, and are prevented from shifting by the usual checknuts 36. The contact points 35 are contacted by similar contact points 37 on riders or resilient blades 38 secured to the sides of the armature 4. The natural period of vibration of the armatures 4 may be varied by moving the sliders 39 back and forth along the said armatures. The said sliders 39 may be fixed in any definite position by tightening the set screws 40, and are so adjusted that their natural periods of vibration are in resonance with the pulsations of the alternating current passing through the electromagnets 10.

The quantity of magnetism induced in the cores of the electromagnets 10 by the permanent magnet 22 may be varied by adjusting the screw 29 to vary the distance between the yoke 14 and the arm 24. The greater the per cent of magnetism so picked up by the cores, the more intense will the vibration of the armature be for a given value of alternating current. The pole pieces 9 are, of course, of the same polarity, being alternatively strengthened and weakened by the alternating current. Regardless of the amount of current in the coils, the intensity of the vibration can only be determined by the difference of pull between the pole pieces 9 on the armature, and this difference is determined by the amount of permanent magnetism transmitted to the cores. This magnetism is alternately chopped out by the action of the alternating current.

Any suitable frequency of alternating current may be used, but the conventional frequency of sixty cycles per second is deemed preferable, the armatures 4 being tuned thereto. Each of the vibrators really constitutes an electric synchronous motor which operates on a surprisingly low current. By winding the coils of the electromagnets 10 to about five-hundred ohms resistance, the armature can actually be kept in synchronism with the alternating current on as low a valve as one milliampere of current. The effect of the currents from the telegraph transmitters on the vibrating reeds is practically negligible, for the obvious reason that the vibrating reeds are not in resonance with the irregular pulsations of the telegraph current.

The current from the main line, of course, passes through post 5, reed 4 and thence alternately to the respective branch line posts 32 through the contacts 35 and 38 as the reed 4 vibrates from one side to the other.

Having thus fully described this invention, I hereby reserve the benefit of all changes in form, arrangement, order, or use of parts, as it is evident that many minor changes may be made therein without departing from the

spirit of this invention or the scope of the following claims.

I claim:

1. A vibratory distributor of electric current comprising a pair of electro-magnets each having a core, a yoke connecting the core ends of like polarity together and a permanent magnet mounted for adjustment with relation to the yoke. 70

2. A vibratory distributor of electric current comprising a pair of electro-magnets each having a core, a yoke connecting the core ends of like polarity together, a permanent magnet mounted for movement to permit adjustment thereof toward and away 80 from said yoke and means for limiting the movement of the permanent magnet toward the yoke. 75

3. A vibratory distributor of electric current comprising a pair of electro-magnets each having a core, a yoke connecting the core ends of like polarity together, a permanent magnet mounted for adjustment with relation to the yoke and an armature mounted for movement and adapted to be alternately attracted toward the poles of the electro-magnet when an alternating current therethrough weakens one electro-magnet and simultaneously strengthens the other, and vice versa. 90 95

4. A vibratory distributor of electric current comprising a pair of electro-magnets each having a core, a yoke connecting the core ends of like polarity together, a permanent magnet having its poles mounted for movement toward and away from said yoke, adjustable means for limiting the movement of one of said poles toward the yoke, and an armature mounted for vibratory movement between the poles of the electro-magnets 100 when an alternating current is passed therethrough and simultaneously weakens one magnet and strengthens the other, and vice versa. 105

5. A vibratory distributor of electric current comprising a pair of electro-magnets each having a core, a yoke connecting the core ends of like polarity together, a permanent magnet having a core mounted for pivotal movement and with one of its ends juxtaposed with relation to the yoke, means for varying the inclination of the permanent magnet about said pivot and an armature mounted for vibratory movement between the poles of the electro-magnet and adapted to 110 be attracted alternately toward the free ends of the poles when an alternating current is passed through the electro-magnets and weaken said current in one magnet and strengthen the current in the other magnet 115 120 and vice versa. 125

6. A vibratory distributor of electric current comprising a pair of electro-magnets each having a core, and arranged in spaced parallel relation, a yoke connecting the core 130

ends of like polarity together, a frame disposed over the other ends of said magnets, a permanent magnet pivoted to the frame, means carried by the frame for shifting the position of the permanent magnet, said shifting means adapted to vary the angle of in-

clination of the permanent magnet with relation to the electro-magnets and the cores thereof.

In testimony whereof I hereunto affix my ¹⁰ signature.

EUGENE SIXTEN SANDBERG.
